ELECTRON TUBE

Donald Graydon Haines, Bloomfield, N. J., assignor to Radio Corporation of America, a corporation of Delaware

Application May 30, 1933, Serial No. 673,571

8 Claims. (Cl. 250—27.5)

This invention relates in general to electronic tubes and more particularly relates to tubes of the cathode ray type which employ an electron beam or beams to control the operation.

5 In a more specific sense, the invention is directed to particular types of anodes to use with tubes of the above described type.

In constructing the usual cathode ray type of tube there is provided a source of electrons and, 10 where desired, a control grid or the equivalent, an anode through which the developed electrons are projected in the form of an electron pencil, suitable deflecting fields, which may be either electrostatic or electromagnetic, or a combination 15 of both, as well as usually some form of means, such as electrostatic or electromagnetic, for focusing, and in certain uses of the tube, for example in television, there is provided a screen structure which is caused to become fluorescent upon the bombardment of the cathode ray pencil 20 thereupon.

Many and varied uses for cathode ray tubes have already been proposed among which is its use as an oscilloscope in which it is possible to observe certain phenomenon and to visualize certain 25 electrical wave formations. Other uses are for both the transmission and reception of television images, and still other uses are as frequency multipliers. Thus, in general, tubes of this type have wide application and also may be used in other fields than those above suggested.

By the present invention, one of the primary 30 objects is to produce a tube of the cathode ray type in which it is possible to obtain variations in the anode current flowing through the tube in accordance with varying displacements or deflection of the cathode ray pencil generated therein. So arranged the tube finds particular application for use as a frequency multiplier.

40 Still other objects of the present invention will become apparent from a consideration of the present specification and claims when read in connection with the accompanying drawing wherein:

45 Fig. 1 thereof illustrates a tube of a preferred form by which frequency multiplication can be obtained; and

Fig. 2 illustrates a view of the anode assembly viewed on the line 2—2 looking in the direction 50 of the arrows.

According to the prior art, as particularly exemplified by patent to Van der Bijl, No. 1,613,626, granted January 11, 1927, provision has been made for the use of a cathode ray tube as a frequency multiplier. When so arranged the

tube is constructed so as to provide a plurality of distinct anode members certain of which are connected so as to feed the output current in one direction and certain others of which are connected so as to feed the output current in an opposite direction. The present invention, however, departs somewhat from the general arrangement provided by the Van der Bijl construction, in that, it is possible to obtain a continuous current in contrast to any interruptions in the current flow produced during the time the electron beam is moving between spaced anode elements. Further, the present invention provides distinct improvements over the arrangements of the prior art by making use of the different secondary electronic emission effects of different materials to maintain and produce changing strength currents flowing in accordance with changing deflections of the electron pencil or beam within the tube.

If reference is now made to the drawing it will be seen that the cathode 1 is provided as an elongated cathode which is suitably shielded by means of a shielding member 2 which provides ways and means by which the generated electrons are caused to flow toward the various anode members, to be later described. Between cathode 1 and anode 4 there is provided what has been generally designated as an accelerator grid 3. To this grid any desired modulation signals may be supplied so as to vary in accordance with the strength of the modulation signals the electron density of the electron pencil which is caused to be developed by the cooperative action of the cathode 1 and the apertured plate member 4 serving as a first anode member within the tube.

To provide for suitable deflection of the generated cathode ray pencil, conventionally designated as 5, there has been provided a plurality of deflecting plate members 6 and 7 to which deflecting voltages of any desired frequency may be applied.

Toward the end of the tube there is provided the anode 8 and auxiliary anode assembly 11. The anode 8 is composed of a series of rectangular shaped conductors 9 whose number, shape and size depend upon the frequency multiplication or the wave form desired or the size of the cathode ray beam employed. Between the various rectangular conductors 9 there is provided a spacing of a width which may or may not be equal to the width of the conducting strips. This spacing area is preferably in the form of a mesh 10 which extends over the area immediately behind the conducting members 8. The conduct-

ing members 8, which are preferably formed of nickel suitably carbonized or some other material which has low secondary emission properties such as carbonized nichrome, for example, are attached to the open mesh 10 by welding or other suitable means. The open mesh 10 is preferably formed of nickel wire which has high secondary emission properties.

In this manner it will be seen from the construction that the anode 8 is formed of alternate strips or areas of carbonized nickel 9 suitably attached to a sheet or strip of nickel mesh 10 in such manner that the solid portion and the mesh areas are alternately in the path of the electron beam 5 as it is passed or directed across the anode surface 8 by the application of controlling or deflecting voltage to the electrostatic deflecting plates 6, 7.

Immediately to the rear of the anode assembly 8, above described, there is provided still another anode 11, termed an "auxiliary anode", which is preferably constructed of a sheet of nickel. This sheet of nickel is so formed as to present a rough surface on the front face. Such a surface which comprises, for example, projecting edges may be suitably made by punching small holes, or by suitably pressing small holes through from the back and then securing, by welding or any other well-known means, a second sheet of nickel to the perforated sheet in order to block the perforations. This second nickel anode 11 may then also be carbonized in order to reduce secondary emission.

At one end of the envelope 12 which encloses the electron gun structure comprising the cathode 1, the electron directing member 2, the grid 3 and the apertured plate 4 serving as a first anode for the tube, are suitably mounted. Operating voltages are supplied to these various elements by way of suitable conductors or wires passing through the press member 13 formed in the end of the tube at which the electron gun is mounted. The cathode 1 which emits the electrons to form the cathode ray is preferably indirectly heated, although the operation of the tube is in no way affected if the cathode is heated directly. At the opposite end of the tube envelope 11 there is a second stem member 14 through which lead wires 15 and 16 to supply operating voltage to the two separate anode members may be employed. In practice, the anode member 11 should be operated at a higher potential than the anode member 8.

From this construction so far described, it can be seen that when the electron pencil is focused on one of the carbonized strips of the anode member 8, the current to this anode is high, and consequently the current to the other anode member 11 is low. However, as soon as deflecting voltages are applied to the deflecting electrodes 6 and 7 the cathode beam is moved so that it falls upon one of the mesh portions of the anode 8 in which event a number of the electrons comprising the electron beam pass through the interstices of the mesh and are collected by the carbonized nickel anode member 11. At the same time other electrons of this same cathode ray beam 5 strike the mesh wires 10 and cause the release of secondary electrons from these wires, of which a large percentage are attracted to the anode member 11. The mesh 10 should be treated so as to have the property of emitting secondary electrons. In the case where a nickel mesh is employed the wires should be clean and have a smooth shiny surface. In this example and under the conditions when the electron pencil is striking or passing through the mesh portion the current in the anode

8 is reduced to a minimum and the current in the anode 11 is a maximum. Conversely, as above defined, the current in the anode 11 is a maximum when the beam is focused upon the mesh portions of the anode 8 and a minimum when focused upon a solid portion of the anode 8. So designed, it is quite apparent that the tube herein described will serve, upon deflection of the electron pencil generated from the cooperative action of the apertured plate member 4 and the electron source 1, when the two anode members 8 and 11 are connected with an external circuit, to produce in the external circuit a multiplied frequency of the controlling frequency.

The degree of multiplication will be determined in accordance with the number of discrete and independent sections into which the anode 8 is divided so as to distribute conducting and mesh-like sections or areas to the electron ray developed within the tube.

This frequency multiplication may be expressed mathematically by the equation $F=N_e f = (N_e - 1)f$ where f is the frequency applied to the deflecting plates 6 and 7; N_e is the total number of strips or plates if an even number; N_o is the total number of screen strips or plates if an odd number; and F is the frequency set up or developed in the external circuit.

If, however, the plates are arranged in a circular order, that is, so each plate is sector-shaped, and alternate plates are of different characteristics, the developed frequency will then be a function of the number of pairs of plates, since for one complete cycle of the impressed frequency the cathode ray beam or pencil will traverse each segment once. This feature may be expressed mathematically by the equation $F=Pf$, where F is the frequency set up or developed in the external circuit, P represents the number of pairs of plates, and f is the frequency applied to the deflecting plates to deflect or sweep the cathode ray beam across the plates.

From the above description it is apparent that many modifications and changes may be made without departing from the spirit and scope of this invention and I therefore believe myself to be entitled to make and use any and all of these modifications insofar as they fall fairly within the spirit and scope of the invention to be hereinafter defined in the appended claims.

Having thus described the invention, what I claim and desire to secure by Letters Patent is the following:

1. An electron device comprising a cathode and an anode, between which an electron beam is developed by the application of suitable voltages, a second anode formed of alternate sections having high and low secondary electronic emission properties, an auxiliary anode adjacent the second anode and having low secondary electronic emission properties of substantially the same order as the low secondary electron emitting portion of the second anode, means for causing the electron beam to traverse the several sections of the second anode member.

2. A cathode ray tube comprising means for developing a cathode ray, an anode structure upon which the developed cathode ray is adapted to impinge, said anode structure being formed of a mesh-like material having high secondary electronic emission properties, a plurality of sections of low secondary electronic emission properties secured to the mesh-like structure and interposed between said structure and the

electron source, an auxiliary anode having low secondary electronic emission properties positioned adjacent said second anode and adapted to receive the electron beam passed through the 5 mesh-like sections of said second anode, and means for causing the developed electron beam to traverse alternately the sections of the second anode.

3. An electron device for producing variations 10 of anode currents which comprises a cathode and an anode, a second anode for receiving the electron beam, said second anode comprising alternately arranged solid and partially solid sections electrically connected, the solid sections being 15 designed to emit a small quantity of secondary electrons and the partially solid sections being designed to emit a large quantity of secondary electrons, an auxiliary anode substantially adjacent the second anode.

20 4. An electronic device comprising an envelope including a metallic mesh-like material having relatively high secondary electronic emission properties, a plurality of substantially equal area metallic sections having relatively low secondary 25 electronic emission properties secured to the mesh-like structure and dividing the structure into alternate sections of high and low secondary electronic emission properties, an electron source, and means for causing the electronic discharge to traverse the several sections of the electrode structure.

5. An electronic tube comprising an envelope including a metallic mesh-like material having relatively high secondary electronic emission properties, a plurality of substantially equal area metallic sections having relatively low secondary electronic emission properties secured to the mesh-like structure and dividing the structure 30 into alternate equal area sections of high and low secondary electronic emission properties, an electron source, an auxiliary electrode arranged adjacent the sectional electrode and more remote from the source of the electron discharge, said auxiliary electrode having low secondary electronic emission properties and adapted to be subjected to the action of the electron discharge 35 during time periods concurrent with the subjection of the area of the first electrode relatively high secondary electronic emission properties of the electron discharge, conductors within the tube and extending outwardly through the wall thereof so that an external circuit may be electrically connected with the multi-section electrode and the auxiliary electrode, and means for moving the electron discharge over the area 40 of the multi-section electrode.

50 55 6. An electron device comprising a plurality

of electrodes, means for developing between the electrodes an electronic discharge, a multi-sectioned electrode positioned in the path of the discharge, said electrode having alternate sections of high and low secondary electronic emission properties under the action of the electron discharge, an auxiliary electrode adjacent the multi-sectioned electrode, said auxiliary electrode having low secondary electronic emission properties corresponding to one series of portions of the multi-section electrode, conductors connecting with said electrodes and extending outwardly through the device so that an external circuit may be connected therewith and become electrically associated with the multi-sectioned electrode and the auxiliary electrode, means for causing the developed electron discharge to traverse the several sections of the multi-sectioned electrode member.

7. An electronic frequency multiplying device 20 comprising an electrode structure comprising a metallic mesh-like material having relatively high secondary electronic emission properties, a plurality of substantially equal area metallic sections having relatively low secondary electronic emission properties secured to the mesh-like structure and dividing the structure into alternate areas of high and low secondary electronic emission properties, an electron source, 25 an auxiliary electrode arranged adjacent the sectional electrode and more remote from the source of the electron discharge, said auxiliary electrode having low secondary electronic emission properties and adapted to be subjected to the action of the electron discharge during time periods concurrent with the subjection of the area of the first electrode having relatively high secondary electronic emission properties, conductors arranged within the device and extending 30 outwardly so that an external circuit may be electrically connected with the multi-section electrode and the auxiliary electrode, and deflecting means for moving the electron discharge over the area of the multi-section electrode at 35 a predetermined rate.

8. An electrode structure comprising a plurality of alternate areas of metallic mesh-like sections lying in one plane and alternate solid metallic sections lying in a plane parallel to 40 said first-mentioned plane, said mesh sections and solid sections being electrically connected, the mesh-like sections having the property of emitting secondary electrons in abundance and the solid sections having low secondary emission 45 properties.

DONALD GRAYDON HAINES.
